Primary Examiner — Stacia A Cadmus(57) **CLAIM**

The ornamental design for a RV leveling block, as shown and described.

DESCRIPTION

FIG. 1 is a top perspective view of a RV leveling block showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top perspective view of the RV leveling block, shown in its position of use; and,

FIG. 10 is a bottom perspective view of FIG. 9.

The broken lines shown in the drawings depict environment only that form no part of the claimed design.
